UNITED STATES PATENT OFFICE.

WILLIAM LINDSAY, OF CHICAGO, ILLINOIS.

SIFTING APPARATUS.

1,161,234.

Specification of Letters Patent. Patented Nov. 23, 1915.

Application filed December 28, 1914. Serial No. 879,139.

To all whom it may concern:

Be it known that I, WILLIAM LINDSAY, a citizen of the United States, residing at Chicago, in the county of Cook and State 5 of Illinois, have invented a new, useful, and Improved Sifting Apparatus, of which the following is a description, reference being had to the accompanying drawings, forming a part of this specification, in which corresponding numerals of reference 10 in the different figures indicate like parts.

The object of my invention, generally stated, is to provide a simple, effective and improved sifting apparatus for sifting or 15 screening comminuted material, such, for example, as sand, Portland cement, iron particles, enameling powder, lime, phosphates, gypsum, pigments, flour or analogous substances or materials.

While uniform separation may ordinarily be accomplished with the use of small screens and the operating appliances heretofore employed in connection therewith, new difficulties and complications at once arise, especially in the treatment of the finer materials, if uniformity of result, coupled with relatively high speed, large capacity and economy of construction, maintenance and operation are to become controlling factors. 25 Without intending to limit myself thereto, it is to these latter considerations that my invention is more especially directed. I accomplish said object in the manner herein-after more particularly described and definitely pointed out in the claims.

In the drawings, Figure 1, is a side view in elevation, portions thereof being shown diagrammatically, of a sifting device embodying the features of my invention, Fig. 40 2, is an enlarged fragmentary section, taken upon the line 2, Fig. 1, viewed in the direction of the arrow, there shown, Fig. 3, is a plan view, Fig. 4, is a side elevation showing a modified form, Fig. 5, is a central 45 section of a pulsator or current-interrupter, Fig. 6, is a side view of a modified construction, Fig. 7, is a plan view thereof, and Fig. 8, is a plan view of a still further modification.

Referring to the drawings, 1, Figs. 1 and 2, indicates rectilinear members or side-bars which are arranged parallel to each other and are rigidly connected at the ends by means of cross-bars 2 and 3, Fig. 3, so as to form a rectangular frame. Stretched 50 from the upper surface of the frame thus

formed, is a reticulated screen 4, Figs. 2 and 3, of woven wire, bolting cloth or other suitable material, having a mesh of a predetermined gage adapted to sift materials of varying degrees of fineness, such, for example, as sand, enameling powder, Portland cement or the like. The gage of the screen meshes may range from four or less, to three hundred to the inch, according to the character of the material to be treated. Bars 5, 5, are placed above and rigidly attached in any approved way to the bars 1, with the screen 4, preferably interposed between them so as to aid in securing the latter, 70 while forming guards to prevent the material upon the screen from falling off at the sides. The frame members may be made from any suitable material, such, for example, as metal or wood, but I prefer to use 75 steel, in view of its greater resiliency. I prefer to support the frame at the upper and lower ends and would recommend that the supports be made yielding or resilient, in order to prevent undue noise and jar to 80 surrounding objects, although in other respects, rigid supports may answer equally well. In the example illustrated in Fig. 1, the frame is shown as being suspended by means of coiled springs 6, from fixed points, 85 not shown, said frame being inclined at a predetermined angle to the horizon to permit the coarser material to pass over. A hopper 7, is located at the upper end for delivering upon the screen the material to be 90 sifted. In the example illustrated in Figs. 1 and 2, I have shown brackets or bridges 8, attached by means of bolts 9, to the under faces of the bars 1. Rigidly secured to the brackets 8, are electro-magnets 10, the poles 95 of which are in operative proximity to the bars 1, which, being of magnetic material, serve as armatures therefor. It should be noted however, that in order to prevent noise and wear, the magnets and armatures 100 should not be permitted to make actual contact. An electric current generator 11, is connected by means of leads 12, and 13, and 14, and 15, respectively, to the magnets upon the upper and lower portions of the 105 frame-members. The generator may be of the continuous or alternating type.

It is well known that a bar of metal or wood is subject to vibration throughout its length in wave form like the string of a 110 musical instrument; the rate and amplitude of the vibrations being proportionate to the

relative length and cross-sectional area of the bar. In order to secure the best results, I prefer to take advantage of this natural law, by so placing the electro-magnets 10, and so proportioning the bridges 8, as to cause the points of vibratory stress upon the frame members to conform to the nodes or wave-lengths of the latter when set in vibration. In the example illustrated in Fig. 1, the dotted line 16, is intended to indicate, in a greatly exaggerated degree, the nodes or wave-lines which would occur when setting the bar 1 into vibration. Assuming the illustration to indicate the correct wave-length, it will be seen that the ends of the bridges 8, should be placed substantially at or near the neutral points of the nodes as represented in the drawing.

The operation is as follows: Upon applying the electric current so as to alternately energize and deenergize the magnets 10, in rapid succession, the bar 1, is set in vibration by being first drawn toward the magnet and then released, thereby imparting a like vibratory movement to the screen. The rate of vibration should be proportionate to the character of the material to be sifted; and inasmuch as the vibratory amplitude is modified by the rate, a low rate giving a large, and a high one a relatively small amplitude, it follows that for coarse material, such as very coarse sand, a low rate of, say, thirty-five vibrations per second, may be employed, while for fine material, a rate of three hundred or more per second may be found desirable.

While a given arbitrary rate may be impressed upon a bar by the sheer force of the stress applied, I recommend that the current frequency be made to conform as nearly as possible to the normal vibratory rate which the bar itself would assume if set into vibration by a blow. This may be accomplished by first ascertaining the vibratory rate of the bar as determined by its length and cross-sectional area, and then attuning the frequency of the current generator to it; care being taken to employ the requisite number of magnets and to position them in conformity to the number and length of the vibratory waves. A preferable way, however, and one which I recommend, in order to secure the best results, is to utilize the normal vibration of the bar itself to automatically govern the current frequency. In Fig. 4, I have shown one means by which this result may be accomplished, but I do not wish to be limited thereto, inasmuch as it may be varied without departing from the principle involved. In the figure referred to, 1, indicates the frame-bar to be vibrated, which is the same as those shown in the previous figures, and being connected in like manner with the screen, is given a corresponding reference numeral. Rigidly

attached to the upper end of said bar and arranged at right angles thereto, is a depending arm 17, having a bore 18, therein for the reception of a stationary supporting member, not shown. A fitting 19, is also rigidly attached to the lower end and is provided with a bore 20, for the reception of a like supporting member. Rigidly attached to the lower end of the arm 17, is an electro-magnet 21, the poles of which are in operative proximity to, but separated from a rigid or stationary armature 22. One terminal of said magnet is connected by means of a lead 23, with an electro-generator 24, which, in turn, is connected by means of a lead 25, with a metal boss 26, secured to a diaphragm in the manner hereinafter described, of a current interrupter or pulsator, generally designated by 27. Said interrupter is rigidly attached by means of a screw 28, to the arm 17, which is in electrical connection with the other terminal of the magnet. The current, therefore, would pass from the coil of the magnet, through the lead 23, generator 24, lead 25, and interrupter 26, from whence it would be short-circuited through the arm 17, to the opposite magnetic terminal. The construction of the interrupter is shown in Fig. 5, in which 29, indicates a cup-shaped metallic casing having a boss 30, into which the screw 28, is threaded to secure it to the arm 17. Said casing is provided with an annular shoulder 31, against which is fitted a flexible diaphragm 32, held in place by means of a ring 33. Attached to the inner face of the casing by means of a screw 34, is a carbon disk 35, while a like disk 36, is attached to the inner face of the diaphragm by means of a screw 37, which is passed through the diaphragm and tapped into the boss 26, to which the lead 25, is secured. The disks 35, and 36, are separated from each other and the space between them, as well as that between the diaphragm and the walls of the casing, is filled with a loose body 38, of carbon particles or granules. It will thus be seen that when the electric circuit is closed with the generator, the current will pass through the circuit as generally described, and in doing so, the passage will be through the boss 26, screw 37, carbon 36, carbon filling 38, carbon-disk 35, and casing 29, to the bar 17, and thence to the magnet. The energizing of the latter causes the lower end of the arm 17, to be pulled toward the rigid stationary armature 22. The arm 17, acts as a lever with the support at 18, as a fulcrum, by which the bar 1, is caused to bend with the first impulse of the current. As soon, however, as a given tension is developed in the bar 1, its resiliency causes it to recoil and a vibratory action is induced therein which reacts upon the diaphragm, causing the latter to vibrate as a result of

the corresponding movement of the arm 17, and casing 29. This movement, in turn, serves to vary the volume of the current in relative proportion to the extent and rate 5 of vibration of the casing and the consequent varying relations of the carbon particles. It will be apparent, therefore, that the casing with its diaphragm and carbonaceous filling, will form an interrupter or 10 pulsometer adapted to vary the amplitude of the current in exact proportion to the rate of vibration of the frame-bar 1, and this vibratory action will continue as long as the electric circuit is closed; the rate of 15 vibration being determined by the bar itself, the length and cross-sectional area which constitutes determining factors.

In Figs. 6 and 7, I have shown a modification in which the bridges are placed above 20 the frame bars 39, and 40, respectively, which bars are attached in any approved manner to under-bars 41, with the screen 4, interposed between them, as in Fig. 2. The bars 41, are attached at their upper and 25 lower ends respectively to stationary supports 42, and 43. In the example illustrated, the bridges 44, and 45, upon the bars 39, are staggered with respect to like bridges 46, and 47, upon the bar 40; or in other 30 words, are placed at different intervals upon said bars so as to modify the character of the vibrations of the two bars by reversing the relative directions of movement and thus modifying the effect upon the 35 screen to cause lateral as well as up-and-down waves, the former being indicated by the lines 48, in Fig. 7. This motion would tend to cause the material to be vibrated laterally as well as up and down and would 40 tend toward greater rapidity in sifting. In the example under discussion, it is assumed that the bars 39, and 40, may be made of wood, in which case armatures 49, are rigidly attached to their upper faces to be acted 45 upon by the magnets 10.

In Fig. 8, a still further modification is indicated, in which the magnets 10, are placed at the sides of the bars 50, so as to 50 induce a lateral vibration thereof. In this construction, it is essential that the cross-wires of the screen 51, should be sufficiently slack to permit of an appreciable lateral movement of the bars when the magnets are energized, which action would cause an alternate stretching and loosening of the cross-strands; thereby tending to toss the material upwardly upon the screen. In such a case it is not necessary that the side-bars should be straight, except in the vertical planes of the sides.

I do not wish to be limited to the construction shown, inasmuch as it may be greatly varied. For example, it is immaterial 55 how the magnets are supported in their relation to the frame, whether on or off,

provided they bear a fixed relation thereto, so as to insure the requisite vibration. If held upon fixed supports adjacent thereto, or if mounted thereon, adjacent to stationary armatures, as shown in Fig. 4, the 70 screen frame would have to be attached to stationary supports. It is obvious that a single member only may be utilized to impart vibration to the entire frame. It is also apparent that the screen need not be inclined. 75

What I claim as my invention and desire to secure by Letters Patent is:

1. A sifting apparatus, comprising, in combination, a frame having members 80 adapted to be set in vibration by the direct influence of an electro-magnet, a screen supported by said frame, an electro-magnet in operative proximity to said frame and a source of electricity in circuit with said 85 electro-magnet, the current frequency of which is attuned to the normal rate of vibration of said frame to cause synchronism between the two.

2. A sifting apparatus, comprising, in 90 combination, a screen, a frame adapted to be set in vibration by the direct influence of an electro-magnet, the constituent members of said frame having a predetermined vibratory rate per unit of time, an electro- 95 magnet in operative proximity thereto, a source of electricity in circuit with said magnet and means, controlled by the vibration of said frame for causing the rate of current pulsation to conform to the vibratory rate of said frame. 100

3. A sifting apparatus, comprising, in combination, a frame having rectilinear screen-supporting members, said member having a predetermined normal rate of vibration per unit of time, a screen supported thereby, a plurality of electro-magnets in operative proximity to said screen-supporting members, means for maintaining said magnets in fixed relation thereto, the disposition of said magnets conforming substantially to the normal vibratory wavelengths of said members, a source of electricity and means for causing an intermittent current in conformity to the normal 115 vibratory rate of said frame members. 110

4. In a sifting apparatus, the combination of a screen, a vibratory frame-member adapted to be actuated by direct magnetic influence, said member having a predetermined normal rate of vibration per unit of time, an electro-magnet, a source of electricity in circuit therewith and a pulsatory element interposed in said circuit, the same being actuated to cause an electric current 120 pulsation with each wave vibration of the frame member whereby the rate of pulsation in the magnet may be caused to conform to the vibratory rate of said frame member. 125

5. A sifting apparatus in which is combined a frame-bar, adapted to be directly influenced by an electro-magnet, said bar having a given vibratory rate per second, a 5 screen connected therewith, and electro-magnet in operative proximity to said bar, a source of electricity in circuit with said magnet and a pulsometer interposed in said circuit in vibratory relation to said bar, and 10 controlled thereby, whereby the vibration of said bar may serve to produce a pulsatory current in said circuit when the latter is closed.

6. In a sifting apparatus, the combination 15 with a frame-member adapted to be directly attracted and repelled by an electro-magnet, when energized, said frame having a given normal vibratory rate per second, of a screen, an electro-magnet in operative proximity to said frame-member, a source of electricity in circuit with said magnet and a current interrupter in position to have its 20 interruptions directly controlled by the vibratory action of said frame-member.

7. A sifting apparatus comprising a screen, a supporting frame therefor, said frame being adapted to be set in vibration when lines of stress are applied thereto at an angle to its axis by electro-magnetic action, an armature, an electro-magnet, one of 25 which is adapted to vibrate with the frame while the other is stationary, a source of electricity and means for causing a pulsatory intermission of the current, the rate of 30 pulsation being in harmony with the normal 35

vibratory rate of the frames to maintain synchronism between the two.

8. A sifting apparatus, comprising a screen, a frame having a member adapted to be set into vibration when lines of stress 40 are rapidly applied thereto at an angle to its axis, a bridge-member rigidly attached to said frame-member at predetermined points, an electro-magnet interposed between said bridge and frame-member and a 45 source of electricity in circuit with said magnet, whereby said bridge may serve to resist the pull of said magnet to cause said frame-member to yield to said pull and induce a vibration in said frame-member in- 50 dependently of its supports.

9. A sifting apparatus, comprising, in combination, a screen, screen-supporting members upon opposite sides thereof, electro-magnets arranged in fixed relation to 55 said members for producing wave-vibrations therein, the magnets associated with one member being alternated or staggered in position with respect to the relative positions of those upon the other to reverse 60 the relative wave-actions, a source of electricity in circuit with said magnets and means for causing the current to pulsate or intermit, whereby a sinuous wave-motion 65 may be imparted to the screen in lateral curves.
